UNITED STATES PATENT OFFICE.

THOMAS EDWARDS, OF BALLARAT, VICTORIA, AUSTRALIA.

TLTING ORE-ROASTING FURNACE.

No. 825,446.

Specification of Letters Patent.

Patented July 10, 1906.

Application filed August 7, 1905. Serial No. 273,102.

To all whom it may concern:

Be it known that I, THOMAS EDWARDS, a subject of the King of Great Britain and Ireland, residing at Ballarat, in the State of Victoria, Commonwealth of Australia, have invented certain new and useful Improvements in Tilting Ore-Roasting Furnaces; and I do hereby declare the following to be a full, clear, and exact description of the invention, such as will enable others skilled in the art to which it appertains to make and use the same.

This invention relates to reverberatory furnaces of elongated form wherein ores or mineral compounds can be effectually roasted and treated in large quantities and with consequent economy.

In the "Edwards" tilting furnace having rotating rabbles a disadvantage is found to exist in that its capacity is limited, because the width of the furnace has been limited by the circle swept by the rabble-arms. Finding the output of these furnaces was thus limited by their widths, the rabble-arms were made long in order to secure greater width, and therefore greater roasting capacity; but it was then found that long arms became unstable in practical work and caused also excessive strain on the rabble-stems and other parts, which involved stoppages, repairs, and expense. It was also found that the intersections of the areas swept by rotating rabbles set in a single longitudinal row, as has always been the system in the Edwards tilting furnaces, did not afford as satisfactory and efficient a means of very thoroughly agitating and stirring the ore as do rabbles arranged as in the invention about to be described.

I now provide a plurality of intersections of each rabble-hearth area by other rabble-hearth areas as will appear by the following. I combine with the tilting furnace multiple rows of rabbles, and this permits of short-armed rabbles being used, a matter of importance for the reasons aforesaid and for others notable in tilting furnace practice.

The invention comprises other features novel in the Edwards tilting furnace, having the effect of economizing much heat hitherto wasted, the result being greater output on less consumption of fuel.

This furnace may now be of any width and capacity. It will be set to work horizontally or at an incline, being adjusted to accommodate all classes and grades of ores, and a

rapid and a more perfect roast is promoted than formerly.

The drawings herewith illustrate parts of an ore-roasting furnace according to this invention, though any useful or well-known parts not shown are or may in practice be added, while a number of parts shown for greater clearness are not here claimed.

Figure 1 represents a side elevation; Fig. 65 2, a plan view with part broken out to show some interior parts; Fig. 3, a longitudinal sectional view omitting rabbles and top gear; Fig. 4, an end elevation, partly in vertical section; Fig. 5, an end view, and Fig. 6 a plan view, of details.

The heavier end of this furnace is the supported end shown provided with tilting means. Rabbles are not shown except in Fig. 4, as any suitable rabbles may be used. 75 In Fig. 2 suitable relative positions of the arms 1 (also called "feet") of four adjoining rabbles are shown dotted, and the hearth areas 2 of various adjoining rabbles are dotted to show plurality of intersections. The 80 rabbles are driven by turning wheels 3, which are fixed on the rabble-spindles by means of pinions 4 on a plurality of longitudinal lines of overhead shafting 5, suitably driven as by gearing actuated from pulley 6. 85 In the drawings the teeth of the various gear-wheels are not shown. Pulley 6 is so positioned relatively to the pivots that the tilting will not interfere with the driving of the pulley. 90

At each side under the furnace, near the center of its length, is a pivot 7, so that the furnace may be tilted, or there may be trunnions or pivots not underneath.

The furnace-body is of metal in girder 95 form with longitudinal beams 8, connected by vertical or equivalent stays 12 and horizontal tie-bolts 13, and is lined with suitable heat-resisting material, and contains an upper chamber 20 for the rabbles and ore and 100 a subdivided longitudinal under chamber having compartments, as 22 21, for the entrance and exit, respectively, of highly-heated gases and furnace products, 23 showing a partition-wall in the under chamber, 105 but, as shown, of less length than that chamber. Both upper and lower chambers have any suitable regulatable apertures for inspection, cleaning, and for, when desired, the passage of air. This girder-furnace body 110 rests on or is supported partly by pivots 7, being also held and supported at one end

with means for raising and lowering the furnace at one or both ends. The said means may be a pair of pistons simultaneously hydraulically actuated, or may be, as shown at 5 9, screws carrying wheels 9^a, adapted to be turned by worms 9^b on transverse shaft 9^c in nuts 9^d, fixed to a bed 11, 10 showing a joint or pivotal connection of a bracket holding the screw-head to a corner of the furnace- 10 body. In Fig. 4 the pivots 7 and their supports are only partly shown, so as to allow the tilting means to appear more clearly. The rabbles 14 are disposed in two or more 15 lines, each rabble separately, and all collectively being driven in positive relation one to the other. They transfer the ore from one to another continuously, materially, and longitudinally from the end of the furnace, having means for the feeding in of ore 15 to the 20 end having means of ore-discharge, (shown by chutes 16,) this end also having the fireplace and its accessories.

The furnace has, as Figs. 2, 3, and 1 show, a fume-outlet 17 for gases from over the 25 hearth and a second fume-outlet 17^a for gases from compartment 21. Outlet 17^a has a damper 18^a, which when raised by any suitable means (not shown) allows the admission of hot gases into the flue 19 of the 30 chimney-stack or the like. Fume-outlet 17 has a damper 18, which when raised allows the highly-heated gases to pass direct from over the hearth into flue 19; but when damper 18 is closed such passage is prevented, and 35 there is then a passage and an opening from 17 down into compartment 22. A lower part of outlet 17 is marked 17^b in Fig. 1. (Shown by breaking away part of outlet 17^a.) The upper part of outlet 17 is marked 17^c. 40 The end of outlet 17^a is broken off in Fig. 3 to show the end of outlet 17. The gases entering compartment 22 pass along the same and turn into compartment 21 at the end of 45 partition 23, as indicated by dotted arrow in Fig. 2, and after traversing 23 enter flue-outlet 17^a and thence reach flue 19, as indicated by arrows in firm lines. There is a raised wall or bridge 17^d at the hearth-feed end to prevent strong draft carrying away ore, which 50 would otherwise thus be lost. When it is not desired to use the under chamber for the continuous circulation therethrough of heated gases, the said under chamber may first be filled with heated gases by inducing the 55 circulation, and then by closing damper 18^a and opening damper 18 further circulation is prevented.

When it is desired to cool the hearth, the side inlets thereto may be fully opened, as 60 well as the inlets to the under-chamber along the sides thereof, and circulation of hot gases into the under chamber is then not permitted. Each damper is adapted to be raised or lowered to the extent desired independently.

The two entrances 27 27^a to flue 19 are each larger than the ends of the fume-outlets 17 and 17^a, projecting into said entrances; but the space around the said ends is completely closed by plates 28 and 28^a. Each of these 70 plates is adapted to slide in suitable guides 30, so as to rise and fall as the furnace is tilted.

30^a is a tie-bar.

29 shows an aperture in plate 28, through which part 17 projects, and plate 28^a is similar.

The parts shown in Figs. 5 and 6 are on a larger scale than the other figures.

There may be any suitable framing, connections, couplings, bearings, and the like supported upon the furnace-top to position the longitudinal shafting and the rabble-stems, and in such manner that any desired rabbles may be taken out through holes in the furnace-top (shown at 25) when said holes are relieved from means used to close them during the working of the furnace. The said framing and other parts are marked 24.

The shaft of pulley 6 is made to operate intermediate gearing 26^a, driving spur-wheels, 90 26, which turn driving-shafts 5 in opposite directions simultaneously.

In practice tilting makes the feed end the higher. I may construct the furnace with a support at the feed end operative when the 95 furnace is level. As shown, the flue-apertures 27 and 27^a have their bases so operative by supporting outlet ends 17 and 17^a. Parts, as 9 to 9^d, act as tilting means and as supports and holding means also.

Modifications may, however, be made in various details within the spirit of this invention. For example, a single slide-plate instead of two may be used.

What I do claim as my invention, and desire to secure by Letters Patent of the United States, is—

1. An ore-roasting furnace, having a pair of longitudinal chambers, one above the other, and a connection between them, the upper 110 chamber being for ore, a plurality of lines of rabbles in the upper chamber having the intersecting hearth areas, the said lower chamber having the longitudinally-extending partition therein and dampers controlling the 115 fume-outlets of the said chambers, substantially as described.

2. An ore-roasting furnace having a pair of longitudinal chambers, one above the other, and a connection between them, the upper 120 chamber being for ore, rabbles in the upper chamber, the said lower chamber having longitudinally-extending partitions therein, and dampers controlling the flue-outlets of the said chambers, substantially as described.

3. An ore-roasting furnace comprising an ore-roasting chamber, a lower chamber, divided to make a circuitous channel for the hot gases, a flue, both of said chambers being adapted to discharge into the said flue at the 130

same end of the furnace, and damper means for controlling the discharge of the gases either into the flue direct or into the lower chamber and thence into the said flue, substantially as described.

4. An ore-roasting furnace comprising the two chambers, one above the other, and the upper one being for ore, a flue, passages leading from each of the said chambers into the flue, damper means controlling the discharge

of gases either into the lower chamber or into the flue and damper means controlling the passage from the lower chamber to the said flue, substantially as described.

In witness whereof I have hereunto set my hand in the presence of two witnesses.

THOMAS EDWARDS.
